UNITED STATES PATENT OFFICE.

CHARLES O. DEIST, OF OTTAWA, ILLINOIS.

POULTRY-MARKER.

1,084,407.

Specification of Letters Patent. Patented Jan. 13, 1914.

Application filed January 15, 1910, Serial No. 538,250. Renewed November 17, 1913, Serial No. 801,552.

To all whom it may concern:

Be it known that I, CHARLES O. DEIST, a citizen of the United States, residing at Ottawa, in the county of La Salle and State of Illinois, have invented a new and useful Poultry-Marker, of which the following is a specification.

This invention relates to poultry markers of that general class commonly known as leg bands, and has for an object to provide a simple and durable leg band that may be easily applied to the bird and will remain positively locked in its applied position until released by manual operation.

One of the fundamental requirements of a leg band is that it must not bind the leg of the bird tightly as this would interfere with the circulation of the blood and impede the growth of the chick. Another requirement is that the band must be held against undue contraction so as not to injure the bird and against undue expansion so that it will not be lost from the bird. To attain these ends I provide a band of pliable metal having two ears on either side of one end that form a means of fastening the ends of the band together so that the band cannot be accidentally disengaged from position.

In the accompanying drawing forming part of this specification,—Figure 1 is a side elevation of a leg band constructed in accordance with my invention. Fig. 2 is a perspective view of the leg band illustrating the first movement of forming the lock. Fig. 3 is a perspective view of the leg band illustrating the second movement of forming the lock. Fig. 4 is a perspective view of the leg band illustrating the final movement of forming the lock.

Referring now to the drawing in which like characters of reference designate similar parts in the views shown, it may be seen that the leg band 1 consists of a single band or strip of pliable metal having formed upon one end a pair of spaced ears 2 extending from one of its longitudinal sides and a similar pair of spaced ears 3 extending from the other of its longitudinal sides, the ears upon both sides of the band having their longitudinal diameters coinciding. The dimensions of the band are uniform throughout its length, breadth and thickness except at the points where the ears 2 and 3 occur and at these points the length and thickness dimensions remain constant while the breadth dimension is increased to the extent

of the sum of the lengths of the alined ears at the opposite edge of the band; which increase however is less than the breadth of the major portion of the band plus twice its thickness. Upon the band may be stamped numerals, letters or other designating characters as desired so as to distinguish the bird to which the band is applied from its mates.

In attaching the band to a bird the band is bent so as to encircle the leg in which position the ends of the band will overlap, as shown in Fig. 2. When the band has been upon itself and pinched so as to tightly engage the leg of the fowl, the ears 2 are bent over the outer face of the band and pinched so as to clamp the band in the desired position. The free end 4 of the band is then bent back upon itself, as shown in Fig. 3, and the ears 3 bent so as to engage the outer face of the said end. The ears 3 are then pinched together so as to tightly impinge against the outer face of the end 4. The extreme end 5 of the band is then looped upon itself and pinched so as to tightly engage the outer faces of the ears 3 which operation completes the forming of the lock.

The ears 2 and 3 by being spaced some little distance apart enable the operator to readily manipulate the band when forming the lock. It is evident that by forming three folds on that portion of the band which is folded through the ears, a positive lock is formed which cannot become unfastened unless by manual operation. As the extreme end 5 of the band is tightly impinged against the outer face of the ears 3, the latter cannot become pried out from their operative position and permit the end portion 4 of the band to escape as would be the case were this final fold not made in the leg band. It is evident that a band of this character cannot contract since the ears 3 by their abutting contact with the end portion 5 of the band prevent the eared end of the band from sliding around the inner periphery of the band. By reason of the fact that the pairs of ears are spaced from each other and by reason of the fact that the ears are not of such length as to have their ends meet when they are bent around the portions of the band there is ample room for the operator to insert the tip of a finger for the purpose of bending the said ears back. If the ears were to meet at their ends about the plain portion of the band it might be necessary to use an instrument in order to bend them

back after they have once been bent over the plain portion of the band. This is thought to be avoided in the present invention for it is the aim that the band may be applied and removed without the use of instruments or tools. Therefore, it will be seen that the relative lengths of the ears with respect to the breadth and thickness of the strip is a matter of importance. Again as this band 10 possesses special utility and is especially adapted to be applied to the leg of a fowl, it is essential that the band shall be as small and as light as possible and devoid of projections of any kind when applied, which 15 would tend to catch in and collect grass or other particles of trash. Therefore, the band is of uniform dimensions throughout except at the points where the ears occur and when the said ears are bent down they 20 are concealed and are prevented from accumulating trash. In fact the material of which the band is formed is so thin that when the band is applied it resembles very closely a continuous plain ring without projections of any kind.

The poultry marker herein disclosed, is ordinarily fashioned from relatively thin material, and is preferably fashioned from zinc, that it may not corrode. The band, 30 therefore is pliable, and if there are any projections upon the outer face of the band, when the same is disposed in annular form, it has been found in practice that the fowl will pick at the projections.

Referring particularly to Fig. 4, it will be seen that all of the tongues 2 and 3 are housed, which is obviously desirable, since the tongues 2 and 3 are of small area, and may readily be picked open by the fowl, permitting a loosening of the band. The end 40 5 of the band as shown in Fig. 4, houses the ends of the tongues 3. At the same time,

the end 5 terminates flush with those edges of the tongues 3 which are adjacent the tongues 2. The end 5 is, therefore, made as 45 short and as stiff as possible, constituent with a covering of the tongues 3. Because the end 5 is short and stiff, and because it is of equal width with the band, the end 5 is not readily picked open by the fowl. Noting 50 Fig. 3 it will be observed that the tongues 3 at their adjacent ends are spaced apart. Therefore, when the end 5 is folded over the tongues 3, as shown in Fig. 4, a nail or like 55 implement may be inserted between the ends of the tongues 3, beneath the end 5 of the band, for the purpose of prying the band open.

What is claimed is:

A poultry marker fashioned from a strip 60 of pliable material provided upon its opposite edges and at one end with pairs of oppositely disposed primary and secondary tongues, the tongues being bent to overhang the strip, the free end of the strip being bent 65 across the outer faces of the secondary tongues and being extended beneath the primary tongues and reversely bent to cover the ends of the primary tongues, the pairs of tongues being spaced apart and the ends of the primary tongues being spaced apart; the strip being imperforate from end to end and the tongues constituting the sole outstanding elements upon the edges of the strip; and the end of the strip terminating 75 flush with the edges of the primary tongues.

In testimony that I claim the foregoing as my own, I have hereto affixed my signature in the presence of two witnesses.

CHARLES O. DEIST.
